United States Patent Office

Des. 218,225
Patented Aug. 4, 1970

218,225

CAN

Carl William Heinle, Short Hills, and Sydney Johnstone Wallace, Allendale, N.J., assignors to American Can Company, New York, N.Y., a corporation of New Jersey

Filed Aug. 29, 1969, Ser. No. 18,921

Term of patent 14 years

Int. Cl. D9—07

U.S. Cl. D9—218

FIG. 1

FIG. 4

FIG. 2

FIG. 3

FIG. 5

FIG. 1 is a top plan view of a can showing our new design;

FIG. 2 is a front elevational view;

FIG. 3 is a fragmentary view of the upper portion of the can looking from the right of FIG. 2;

FIG. 4 is a fragmentary rear elevational view showing the upper portion of the can; and

FIG. 5 is a fragmentary view on an enlarged scale taken on the line 5—5 of FIG. 1.

We claim:

The ornamental design for a can, as shown.
